ELECTRICAL MOUNTING DEVICE

Harold G. Johnstone, Plainfield, N. J., assignor to
 Western Electric Company, Incorporated, New
 York, N. Y., a corporation of New York

Application August 18, 1944, Serial No. 550,052

2 Claims. (Cl. 173—324)

1

This invention relates to electrical mounting devices and more particularly to a combined electrical terminal and support and to a device employing such terminals for supporting an electrical unit.

There are many occasions in various electrical arts where it is desirable to simultaneously support a delicate electrical unit and provide for electrical connection of the same to other element of an electrical assembly. Thus, in particular, the delicate slices of crystalline quartz, often coated with a fine layer of metal on one or both sides, which have found so many applications of late, must often be supported and at the same time have their coatings electrically connected to relatively massive terminals for connection to other electrical parts of an assembly. The same may be true of other electrical units, e. g. coils or condensers too delicate and fragile to be dealt with in ordinary ways.

An object of the invention is to provide a simple, reliable mount for an electrical unit which unit has one or more projecting and relatively stiff connection portions or members.

With the above and other objects in view, the invention may be embodied in a mount for an electrical unit having a pair of oppositely extending conductive terminals, the said mount comprising a base, a pair of spaced conductive posts mounted in the base and insulated from each other, a pair of resilient conductive terminal gripping connector members mounted one on each post and having their terminal gripping portions normally spaced apart a distance greater than the span of the terminals of the electrical unit to be mounted, each connector member being formed at its terminal gripping portion with mutually opposed prongs between which a terminal of the electrical unit may be forced to be held thereby, and the parts being so proportioned and related that when both terminals of an electrical unit are gripped respectively between the prongs of the two connector members the terminal gripping portions of the connector members are held spaced less than their normal distance apart against the tension of their resilience and the unit is held therebetween under permanent tension.

Other objects and features of the invention will appear from the following detailed description of one embodiment thereof taken in connection with the accompanying drawings in which the same reference numerals are applied to identical parts in the several figures, and in which

Fig. 1 is a view in side elevation of a mount for

2

an electrical unit and constructed in accordance with the invention;

Fig. 2 is a view thereof on the line 2—2 of Fig. 1;

Fig. 3 is a view thereof on the line 3—3 of Fig. 1;

Fig. 4 is a detached face view of one of the support terminals;

Fig. 5 is a detached face view of a modified form of terminal on a smaller scale;

Fig. 6 is a similar view of another modified form of terminal;

Fig. 7 is a similar view of a third modified form of terminal;

Fig. 8 is a view similar to Fig. 1 of a generalized form, on a smaller scale, and

Fig. 9 is a face view of another form of terminal to receive a cylindrical member.

The embodiment illustrated in Figs. 1, 2 and 3 presents a mount, constructed in accordance with the invention, to support, and to provide electrical connections to the metal coatings of, a slice of crystalline quartz having metal coatings on both sides, such as is familiarly known in the art as a "crystal," tout court. This particular crystal, generally indicated at 20, consists of a thin square slice 21 of crystalline quartz. On the front face (Fig. 1) of the quartz slice 21 is a circular area having a coating 22 of metal thereon with a strip like extension 24 of the coating running out to the left corner 26 of the quartz. On the rear face is a similar coating 23 with a similar extension 25 running to the right corner 27 of the quartz. The combination of the quartz slice or wafer 21 with its coatings 22 and 23 and their extensions 24 and 25 will hereinafter be called simply the crystal and designated as a unit by the number 20.

The mount for the crystal has two relatively large and sturdy metal posts 27 and 28 rigidly secured, parallel to each other and spaced a suitable distance apart, in a block or member 29 of insulating material. A combined terminal and support 30 is mounted on the post 27. This member 30 is a rectangular strip of elastic metal bent to provide a horizontal foot 31 and an upstanding upright 32. The whole may be of any suitably resilient and conductive metal, e. g. spring brass, bronze, steel or the like, which will allow the member 30 to be deformed from its natural shape as shown in broken lines in Fig. 1 to the shape shown in full lines without taking any set. When detached and free, as in Fig. 4, the normal angle between the foot 31 and upright 32 is considerably smaller than when the member 30 is under

permanent tension in its intended use, as in Fig. 1. The foot 31 may be suitably perforated as at 33 in Fig. 4 to slip snugly over the post 27, and be secured thereon with solder as at 34 in Fig. 1. Or the imperforate foot 131 may be spot welded to the flat top of the post, as in Fig. 8, if the metals in question are suitably compatible. The upright 32 is perforated in a suitable location as at 35 to form, on each side of the axis of the upright, a pair of inwardly extending sharp pointed lobes or prongs, such as 36 and 38 pointing back from near the front edge of the upright and 37 and 39 extending forward from near the rear edge of the upright, the points 36 and 37 being originally substantially in contact, and the points 38 and 39 likewise, as in Fig. 4. An identically similar combined terminal and support 40 is mounted on the post 28 in similar fashion.

When the mount is assembled and before a crystal is placed in it, the uprights 32 and 42 stand in their normal positions and slanting away from each other so that the distance between the prong edged perforations or terminal gripping portions of the members 30 and 40 is greater than the span between the terminals 24 and 25 to be gripped by these, as shown in broken lines in Fig. 1; and at this time the points 36, 37, 38 and 39 are flat with the rest of the upright. A crystal 20 is then held in position between the uprights 32 and 42 with its plane perpendicular to the uprights and its corners 26 and 27, respectively, at the centers of the spaces between the four points of each upright. The uprights are then squeezed carefully together until they assume the positions shown in full lines in Fig. 1. In so doing, the four points or prongs 36, 37, 38 and 39 are bowed outwardly as shown by the crystal wedging through between them, and, in effect, become bars digging into the metal on one side of the crystal and engaging in the tiny roughnesses of the quartz to prevent the uprights from springing back into their unstressed positions when the squeezing pressure is released. So effective is this action that when the squeezing pressure is released, the assembly remains in the state illustrated in full lines in Fig. 1, with the crystal under continuous tension along its horizontal diagonal because of the outward pull of the uprights 32 and 42. The tension thus exerted has the additional advantage of effecting and keeping effective an electrical connection between the uprights 32 and 42 and the metal coating extensions 24 and 25, respectively, which is not affected by even heavy jars or vibrations, short of destruction of the crystal, which does not have to be soldered, and which does not become loose or uncertain or variable in its electrical resistance.

The fact that the crystal or other unit is continuously under tension to maintain a tight supporting grip and tight electrical connection between the connector support and the unit is of material importance. Apparatus including fragile units, especially crystals, are employed by all of the armed services in great number and variety, and frequently in situations where severe shocks to the apparatus are unavoidable. Being supported in tension, it is almost impossible for any shock to impose a damaging stress on the unit, as would be the case were the unit supported in compression.

Figs. 5, 6 and 7 show alternative forms of the prongs or points to engage the crystal and are believed to be self-explanatory, beyond noting that the prongs in Figs. 6 and 7 have edges of measurable length instead of points to engage

the crystal, which may be preferable where more than point contact is desired for the electrical connection of the supporting member to the metal coating of the crystal.

In Figs. 8 and 9 are shown a modified form of mount and of support member, particularly adapted to an electrical unit 120 having cylindrical terminals. The aperture 135 in the member 132 is simply a pair of crossed slits, providing four prongs or points 136 to engage the terminal 124. The element 120 is here thought of as a condenser or coil encased in some suitable form of housing with its terminals 125 and 126 projecting from opposite sides of the housing.

Other modifications within the scope and spirit of the appended claims will readily suggest themselves to those skilled in the art.

What is claimed is:

1. A mount for quickly attaching under gripping tension an electrical unit having a pair of spaced conductive terminals, including an insulator, a pair of resilient metal connector members mounted on the insulator and normally slanting upward and away from each other, each of said connector members having an aperture therein providing mutually opposed prongs between which a terminal of the electrical unit may be forced to be held thereby, and the parts being so related that when both terminals of the electrical unit are gripped respectively between the prongs of the two connector members the pronged apertures are held spaced less than their normal distance apart to securely hold the unit under a permanent pulling tension.
2. A mount for quickly attaching under permanent tension an electrical unit having a pair of spaced conductive terminals, including a base, a pair of spaced resilient metal connector members insulatively mounted in the base and normally slanting away from each other and tensioned to pull away from each other, each of said connector members being perforated to form a plurality of inwardly extending sharp pointed prongs between which a terminal of the electrical unit may be forced to cause the prongs to bow outwardly and dig into the terminal, the parts of the mount being so related that when the connector members are squeezed together and the terminals of the electrical unit inserted in the apertures therein and the pressure released the connector members are prevented from springing back to unstressed normal position because of the gripping tension exerted on the terminals of the unit by the connector members.
